TOOL FOR REMOVING CONNECTING RODS

Frank Hendricks, North Vernon, Ind., assignor of
one-half to John H. Gilmer, North Vernon,
Ind.

Application December 15, 1941, Serial No. 423,099

1 Claim. (Cl. 254—100)

My invention relates to a special tool for use in removing connecting rods of engines from passenger cars and trucks, without draining the water or disturbing the head of the engine. I have illustrated the tool as being adapted for the Chevrolet cars and trucks.

Prior to my invention in replacing a connecting rod, it was necessary to draw the water from the engine, remove the engine head, disconnect the ignition system, and then raise the piston through the top of the block or head, which operations are time consuming, and expensive, and are obviated by my invention.

My invention consists of a special tool which, after the pan is removed and the crank shaft turned, and the lower half of the crank case removed, may be readily introduced to remove the connecting rod wrist pin, the object of which is to facilitate this operation, and make it unnecessary to remove the parts hereinbefore mentioned; and with this and other objects in view my invention consists of the parts and combination of parts hereinafter pointed out.

In the drawings:

Figure 1 is a transverse vertical sectional view of an internal combustion engine with the pan at the lower end of the crank case removed in order to facilitate the removal of the damaged connecting rod.

Figure 2 is a similar view showing the bolt normally clamping the wrist pin to the connecting rod replaced by a special tool.

Figure 3 is a view similar to Figure 2 showing my special tool operated to open the clamping jaws of the connecting rod to unlock them from the wrist pin.

Figure 4 is a horizontal section taken on the line 4—4 of Figure 2.

Figure 5 is a horizontal sectional view taken on the line 5—5 of Figure 2.

Figure 6 is a perspective view of the actuating rod and adjustment nut threaded thereon.

Figure 7 is a perspective view of the thrust plate designed to coat with the actuating rod.

The reference numeral 1 designates the cylinder head of an internal combustion engine, in which is mounted a piston 2, the cylinder head terminating at one end in a casing 3 having flanges 4 provided with bolt openings 5.

The lower end of the connecting rod 6 is provided with an enlarged base 7 having flanges 8, provided with bolt openings 9, said enlarged base having the usual bearing 10 in which the crank shaft 11 is sealed. This crank shaft bearing is completed by the lower half 12 which is secured to the base 7 by means of the bolts 13 and 14 as showing in Figure 1. In this figure the pan 15 is shown detached.

5 My improved special tool consists of the thrust bar 16 having a laterally and slightly upwardly projecting end 17 provided with an opening 18, the main body of the bar having a bolt opening 19; the tool further consists of a screw threaded rod 20 on which is mounted a nut 21, said rod having a head 22 provided with a kerf 23a.

10 To remove a connecting rod from an internal combustion engine, remove the pan 15. Then remove the lower half 8 of the crank shaft bearing, turn the crank shaft out of the way, as illustrated in Figure 2, thereby making it possible to allow the piston 2 to be moved down, as shown in Figure 2; then remove the bolt 25 that clamps the wrist pin to the connecting rod.

15 With the parts in the engine and in the portions above set forth, the thrust bar 16 is now secured to the enlarged head of the connecting rod and secured in that position by the bolt 13, as clearly shown in Figures 2 and 3. The rod 20 is then inserted through the opening 18 in the thrust bar and the nut 21 threaded on the rod. The rod is now pushed upward through an opening in the lower wrist pin clamping jaw 23, and then introduced into the threaded opening in the upper jaw 24. With the parts in this position the nut 21 is moved down on the threads of the rod 20 until it is sealed on the thrust bar 16. The nut 21 is then turned on the rod 20 by a suitable instrument thereby forcing it upward, which movement moves the upper jaw 24 of the wrist pin clamp upward away from locking contact with said pin, as clearly shown in Figure 3, whereby the wrist pin is free to be removed, leaving the connecting rod free to be pulled downward and removed. In placing a new connecting rod it is inserted in its proper position, the nut 21 is moved upward on its rod, thereby leaving the jaw 24 free to clamp down on the already inserted wrist pin. The bolt 24 is then secured in position, as are also the lower half 12 of the crank bearing and the pan 15 in proper sequence.

20 What I claim is:

25 A special tool for removing connecting rods from internal combustion engines, comprising a thrust bar one end of which is extended upwardly and provided with a bolt opening, a screw threaded rod extending through said bolt opening, a nut threaded on said rod, said thrust plate having a bolt opening designed to register with a bolt opening in a connecting rod whereby the thrust plate may be firmly clamped to the connecting rod.
